3 Claims. (Cl. 128—188)

1

This invention relates to apparatus for mixing the vapour of a volatile anaesthetic such for example as trichlorethylene with air for inhalation purposes by a patient.

Existing apparatus for the purpose is open to the objection that the percentage of trichlorethylene in the trichlorethylene air mixture increases with increasing temperature owing to the increase in the vapour pressure of the liquid trichlorethylene with temperature.

The present invention has for its object to introduce a device which as the temperature of the apparatus rises, reduces the area of an orifice through which concentrated trichlorethylene air vapour issues while keeping constant, or increasing the area of an orifice through which the diluting air is drawn.

According to this invention the apparatus comprises a vessel in which a quantity of the liquid can be placed, the said vessel being provided with an air inlet for providing air for vapourizing the anaesthetic liquid, the apparatus being provided with a diluting air inlet and a temperature controlled device which as the temperature of the apparatus rises from any cause automatically reduces the orifice through which the concentrated volatile anaesthetic air vapour issues while keeping constant or increasing the area of the orifice through which the diluting air is drawn during inhalation through a suitably arranged inhalation outlet. The liquid may be absorbed by means of a wick or other absorbent contained in the vessel. The thermally operated device may be arranged to provide for automatically altering the relative areas of the orifice through which the concentrated volatile anaesthetic air vapour issues and the area of the orifice through which the diluting air is drawn during inhalation.

In order that the said invention may be clearly understood and readily carried into effect, the same is described more fully with reference to the accompanying drawings, in which:

Fig. 1 is a section of one form of appliance for carrying out the invention.

Fig. 2 is a similar view showing a preferred form of appliance.

Fig. 3 is a section taken on line 3—3 of Fig. 2 looking in the direction of the arrow.

Fig. 4 is a front view of the appliance and

Fig. 5 is a diagram showing the circuit flow.

A form of appliance for carrying out the invention comprises a casing A fitted at one end with a perforated annular plate B which forms a centralizing device and holder for a wick tube

2

C that is packed with a wick D or body of absorbent material that may extend from the bottom of the tube to within a short distance from the top say for example about an inch. The opening in the bottom of the wick tube may be contracted by a conical ferrule C¹ which is fixed therein, and, fastened to the perforated plate, which may be slightly larger in diameter than the casing is a cap E which may be formed with a circle of holes E¹ in the bottom and with a ring of holes E² around its periphery, and such cap may be fitted with an annular tray E³ which may be dished and formed with a flange E⁴ which extends around its opening and contacts with the end of the cap. Fixed to the upper end of the wick tube is an annular plate C² in which is centrally fixed a mixing tube F of smaller diameter than the wick tube that projects through an opening in the top of the casing. Situated within this tube is a small tube G fitted at the bottom with a plate G¹ that rests on the top of the wick and formed in the tube immediately above such plate is a lateral opening G² above which is a circular baffle plate G³.

Fixed on the upper end of the small tube G is a flanged collar G⁴ that rests on a shoulder F¹ in the mixing tube and screwed into such collar is a nipple H that terminates at its upper end in a point H¹. This nipple is formed with a central bore H² with a lateral opening H³ which communicates with a dished recess G⁵ in the top of the flanged collar. The latter together with the pointed nipple forms the bottom of a chamber for a sealed glass phial J which may contain trichlorethylene.

The top of the casing is closed by a cover through which the phial containing portion of the tube passes and such cover is formed with a central recess to receive a nut K which screws onto a threaded portion of the tube F and clamps a plate L together with a portion of the cover A² between itself and a shoulder or abutment on the tube. This plate is provided with two diametrically arranged lugs L¹L². Pivoted in the lug L¹ is a forked lever M which spans the mixing tube F and is provided at its free end with a cross bar M¹ which extends through the prongs of the fork and forms an abutment for a very short arm N of a bell-crank lever that is formed

50 with a long arm N¹ which is situated between the casing A and the mixing tube F and is provided at its free end with a valve plate N² which operates in conjunction with a seating F² that is situated opposite to a lateral opening F³ in the tube and may form part of the wall of a cham-

ber F⁴ that extends around such tube and opening. This lever operates in conjunction with a long blade spring N³ which tends to push the valve plate N² on to the seating.

The forked lever M is provided in proximity to its pivot and at the opposite side of the latter to the cross bar with a bearing O for the conical or rounded end of a rod O¹ which has a very low coefficient thermal expansion. The lower end of this rod is also conical as shown at O² or rounded and is supported in a bearing O³ which may form part of a screw O⁴ that is screwed into a tapped hole in the perforated annular plate B.

To utilise the apparatus a glass phial of trichlorethylene may be placed in the chamber and the cap screwed down until the sharp point breaks the glass. The liquid thus released runs down the small tube and is absorbed by the wick. If the latter has already been saturated excess liquid will drain out through the holes at the bottom of the casing.

Alternatively the filling may be effected by using the cap at the top of the phial chamber as a measuring device for measuring the liquid.

Having charged the apparatus the inhalation outlet A³ is connected directly to a mask which the patient applies to his face, or it is connected to one end of a flexible tube at the other end of which is a non-return valve and an exhalatory valve unit to which is attached the face mask. When the patient inhales, air is drawn through the perforated annular plate and a portion of such air passes through the perforations without coming into contact with the liquid. Some of the air passes through the wick and picks up a high concentration of the liquid vapour. This mixture enters the mixing tube and issues between the seating and the valve plate and then mixes with the outer stream of clear air.

The relative areas of the air holes in the perforated plate and of the annular area between the seating and the valve plate are so adjusted that at a given temperature the desired mixture is obtained.

If now the temperature and therefore the vapour pressure of the liquid rises, the area of the annular orifice is reduced. The casing which may be made of brass expands while the length of the rod remains approximately the same. Although the valve plate is tended to be pushed on to its seating by the spring, it is however held in a certain position through the action of the lever mechanism and the practically non-expanding rod but as the length of the casing increases the spring causes the valve plate to move towards the seating thus reducing the annular orifice area until the levers are again pressing upon the pivot of the rod.

This reduction of the area of the orifice passing strong trichlorethylene vapour will cause a reduction of the proportion passing into the mixture and will thus compensate for the increased strength of this vapour due to the increased vapour pressure of the trichlorethylene.

The preferred form of appliance shown in Figs. 2 and 5 for carrying out the invention comprises a rectangular case 1 to the base of which is attached at one end a vapourizing chamber 2 which is packed with a wick 3 or the like and contains baffles 4 to prevent splashing of the liquid anaesthetic. This vapourizing chamber is also fitted with a tube 5 at right angles or thereabouts to the chamber for charging with the anaesthetic. The inlet of this charging tube is so arranged that when the instrument is hori-

zontal only a definite volume of liquid can be poured therein.

Passing through the centre of the vapourizing chamber is a tube 6 of a material which has a high coefficient of thermal expansion such for example as brass. One end 6A of the tube is open to the atmosphere and the other end is extended to a valve seat 7 inside a chamber 8 hereinafter called the mixing chamber. Passing through the tube 6 is a rod 9 having a very low coefficient of thermal expansion. At the other end of the brass tube which is open to the atmosphere this rod rests on an adjusting screw 10 and its other end protrudes beyond the valve seat 7 so that it is kept clear or open in which position it is retained by means of a spring 12.

Also incorporated in the mixing chamber is an air inlet valve 13 which may be set in a more or less open position. For this purpose it may consist of a flat disc held on one side of a seating 14 by means of one or more screws 15 and clear of the seating on the opposite side by means of a screw 16 which is adjustable so that the valve can be set to the desired opening.

Connected to the mixing chamber is a rubber or other flexible tube 17 Fig. 5 to which is attached a face piece adaptor 18 incorporated in which are two non-return valves 19, 20. This valve 19 acts as an inspiratory valve which allows the patient to inhale air and vapour from the flexible tube and prevents expiration down the tube. The other non-return valve 20 allows the patient to exhale to the atmosphere and prevents inspiration of air therefrom. On the face piece adaptor between these two valves is a branch pipe 21 onto which is plugged the face piece 22.

On inspiration air enters one common inlet 23 into the casing. It is then divided and a portion is drawn through the end 6A of the brass tube beyond the vapourizing chamber and as it passes through such tube it is deflected by a partition 6B therein through holes 6C in the tube, into the vapourizing chamber where it comes in contact with the soaked wick and consequently picks up the anaesthetic vapour. It then returns through another set of holes 6D in the brass tube at the other side of the partition and along the tube to the opening between the valve 11 and the valve seat 7. After passing through such opening it meets and mixes with the other portion namely pure air which has been drawn through the air inlet 13A between the valve 13 and seating 14 to the mixing chamber 8. The percentage of anaesthetic vapour and air in this mixture is mainly dependent upon the amount of opening of the air inlet valve 13 and the anaesthetic inlet valve 11.

As the atmospheric temperature rises the vapour pressure of the anaesthetic also rises and to prevent this resulting in an increased percentage of anaesthetic to the patient the anaesthetic controlling valve 11 is made to close slightly as the temperature rises and to open as the temperature falls. This is due to the combined action of the expansion of the brass tube 6 and negligible expansion of the rod 9 and in this way the gap between the seating 7 and the valve 11 is reduced.

This arrangement results in a consistent mixture of anaesthetic vapour and air to the patient irrespective of ordinary atmospheric temperature variations.

What we claim as our invention and desire to

secure by Letters Patent in the United States is:

1. Apparatus for mixing the vapour of a volatile anaesthetic with air for inhalation purposes by a patient, comprising a vessel in which a quantity of anaesthetic liquid can be placed, the said vessel being provided with an air inlet for providing air for vapourizing said anaesthetic liquid, a mixing chamber being provided with a diluting air inlet and an orifice communicating with said vessel, a temperature controlled device which as the temperature rises from any cause automatically reduces said orifice, through which the concentrated volatile anaesthetic air vapour issues while keeping constant or increasing the area of said diluting air inlet in said mixing chamber through which the diluting air is drawn during inhalation, and suitably arranged inhalation outlet means connected to said mixing chamber for guiding the final diluted anaesthetic vapor to the patient.

2. Apparatus according to claim 1 wherein the liquid may be absorbed by means of a wick or other absorbent contained in the vessel.

3. Apparatus according to claim 1 wherein a thermally operated device may be arranged to provide for automatically altering the relative areas of the orifice through which the concentrated volatile anaesthetic air vapour issues and of the diluting air inlet through which the diluting air is drawn during inhalation.
